UNITED STATES PATENT OFFICE.

ERLE H. HAND, OF STAPLETON, NEW YORK.

CAR SIGNAL DEVICE.

Application filed March 25, 1922. Serial No. 546,663.

To all whom it may concern:

Be it known that I, ERLE H. HAND, a citizen of the United States, residing at Stapleton, county of Richmond, State of New York, have invented a new and useful Car Signal Device, of which the following is a specification.

The object of my invention is to devise a novel construction and arrangement of a car signal device whereby when a car approaches a station or intersecting street the name of the station or street which the car is approaching will be visibly indicated.

With the above and other objects in view which will hereinafter more clearly appear, my invention comprehends a novel car signal device.

It further comprehends a novel construction and arrangement of circuit opening and closing means and novel means for effecting the automatic operation thereof during the travel of a car.

It further comprehends novel contact mechanism, novel operating members and novel guiding means therefor.

It further comprehends novel means for causing the circuit opening and closing member to be retained in the position to which it has been set.

Other novel features of construction and advantage will hereinafter more fully appear in the detailed description of the invention.

For the purpose of illustrating my invention, I have shown in the accompanying drawings a typical embodiment thereof which is at present preferred by me, since this embodiment will be found in practice to give satisfactory and reliable results. It is, however, to be understood that the various instrumentalities of which my invention consists can be variously arranged and organized and that my invention is not limited to the precise arrangement and organization of these instrumentalities as herein shown and described.

Figure 1 represents, in side elevation, a car in conjunction with which signalling devices embodying my invention are employed.

Figure 2 represents a top plan view of the construction seen in Figure 1.

Figure 3 represents, in sectional elevation, a portion of the construction showing more clearly certain details thereof.

Figure 4 represents, in front elevation, a portion of a contact member.

Figure 5 represents, in front elevation, a signal setting member.

Figure 6 represents a section on line 6—6 of Figure 5.

Figure 7 represents a section showing more particularly the manner in which a signal operating member is guided by the car.

Similar numerals of reference indicate corresponding parts.

Referring to the drawings.

1 designates the car which carries a signal 2, see Figure 1, which may be of any desired or conventional type wherein when the circuit is closed the indicator will be advanced so that the name, number or other matter indicative of a station will be visibly indicated at a desired place on the car. The signal is operated by means of any desired type of electric motor, or electric magnets which when energized will actuate the signal. A line 3 leads from the signal 2 to a battery 4 from which leads a line 5 which is connected to a shaft 6 carried by a bracket

7 supported by the roof of the car. 8 designates a plurality of stationary contacts which are electrically connected by the line 9 with the signal 2. The contact 8 is provided with the curved depression 10 in which is adapt-

ed to travel the contact rollers 11 carried by the arms 12 two of these arms being employed see Figures 1 and 3. The arms 12 are carried by a hub 13 loosely mounted on the shaft 6 which latter is provided in its

periphery with a plurality of recesses 14 into which are adapted to partially extend a ball 15 movable in an aperture 16 in one of the arms 12 and a spring 17 is provided in rear of the ball 15, the tendency of which

is to cause the ball 15 to seat in an aperture 14 when it comes into alignment with the aperture 16. The hub 13 has also extending from it the diametrically located arms 18, the ends of which are deflected in opposite directions and carry rollers 19.

The stationary contact member 8 curves downwardly at its ends 20 and 21 respectively, as will be understood from Figure 3. The car has rising from its roof standards

22 which carry channel bars 23 which serve as guides and which are curved outwardly at their ends, as indicated at 24.

In proximity to each station a pair of operating members 25 are secured which are provided with rods 26 by means of which they may be supported at the proper height

above the car roof and these rods are connected with a head 27 from which depends the arm 28 at the lower ends of which is rotatably mounted a roller 29.

5 30 designates a spring member secured to the head 27 by means of fastening devices 31 and its free ends are deflected downwardly and inwardly to form the spring arms 32 and 33, respectively. The head 27 of the operating member is provided at each end with an upper roller 34, a lower roller 35 and an end roller 36 which engage the inner walls of the channel 23.

It will be seen that a number of circuit 15 opening and closing members are employed mounted on the shaft 6, as seen in Figure 2, and it will be understood that the rollers 29 and the spring arms 32 and 33 are positioned on the heads 27 of the operating members 25 20 in such position that they will operate the signal for their respective stations so that the signal corresponding to each station will be set and unset as the car approaches such station.

25 The operation of my novel car signal device will now be readily apparent to those skilled in the art to which this invention appertains, and is as follows:—

When the car seen in Figure 1 is approaching the station at 37, the roller 29 seen at the upper left-hand portion of Figure 1 30 engages the upper roller 11 carried by the arm 12, (which was in the position of the upper roller 19, before engagement), and 35 causes a partial rotation of the hub 13, thereby bringing the lower roller 11 on the opposite or lower arm 12 into contact with the resilient bowed spring member 8, said lower roller 11 riding over the end of said member 40 into the concavity 10, as seen in Figures 1 and 3, thereby closing the circuit through the signal 2, so that the signal or indicator is operated to visibly indicate the station which the car is approaching.

45 When entering the station 38 seen at the upper right hand portion of Figure 1, the same operation is repeated with the appropriate roller 19, carried by the arm 18, which is shorter than the arm 12, and shuts off the 50 circuit.

It will be understood that the hub 13 and its adjuncts is capable of free rotation upon the shaft 6, but is temporarily resiliently locked in its proper positions by the devices seen in Figure 3. The inner walls of 55 the side channel beams 23 effectively coact with the upper and lower rollers 34 and 35 and the end rollers 36, as will be understood from Figures 2 and 7, so that the tripping 60 roller 29 will properly engage the appropriate rollers 11 and 19 at the proper intervals, as is evident.

It will be apparent that the resilient contact devices 8, the arms or brackets 7, carrying the shaft 6 and its adjuncts, as well as

the channel beams 23, can be readily attached to the tops of cars of any standard or conventional type.

The operating members 25 may all be of one standard construction with the tripping 70 roller properly positioned therein and may be installed in proximity to the stations at the proper points by any well known means, which it is unnecessary to describe in detail.

It will now be apparent that I have devised a novel and useful construction of a car signal device, which embodies the features of construction enumerated as desirable in the statement of the invention and the above description, and while I have in 80 the present instance, shown and described preferred embodiments thereof which will give in practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a car signal device, a contact member carried on a car, a shaft mounted above said member, a hub rotating on said shaft, and provided with radial arms arranged in pairs of different lengths, and rollers mounted in the ends of said arms to actuate said contact member for opening and closing an electric circuit.

2. In a car signal device, a contact member carried on a car, a shaft mounted above said member, a hub rotating on said shaft, and provided with radial arms arranged in pairs of different lengths, and rollers mounted in the ends of said arms to actuate said contact member for opening and closing an electric circuit, in combination with a spring-pressed locking device common to said shaft and hub.

3. In a car signal device, a contact member carried on the top of a car, a shaft mounted above said member, a hub rotating on said shaft and provided with radial arms arranged in pairs of different lengths, rollers mounted in the ends of said arms for opening and closing an electric circuit, means for resiliently locking said hub and arms in the proper position with respect to said contact member, a pair of guiding devices mounted on the top of said car, and an operating member positioned along the track-way having its ends provided with rollers adapted to engage said guiding devices and an intermediate disposed roller adapted to engage and trip a roller carried by one of 115 said arms.

4. In a car signal device, a plurality of contact members arranged longitudinally and parallel with respect to each other and supported on a car top, a shaft mounted 130

above said members, a plurality of hubs rotating on said shaft and provided with radial arms of different lengths arranged in pairs, and rollers mounted in the ends of 5 said arms to actuate said contact member for opening and closing electric circuits.

5. In a car signal device, a plurality of contact members arranged longitudinally and parallel with respect to each other and 10 supported on a car top, a shaft mounted above said members, a plurality of hubs rotating on said shaft and provided with radial arms of different lengths arranged in pairs, and rollers mounted in the ends of said 15 arms to actuate said contact member for opening and closing electric circuits, in combination with tripping devices arranged in proximity to a railroad station and adapted to coact with the rollers carried by said arms 20 for rotating the latter and said hub.

6. In a car signal device, a pair of channel beams arranged in horizontal alignment on opposite sides of a car top, contact devices mounted upon the car top intermediately of 25 said channel beams, a shaft above said contact devices, a plurality of hubs rotating on said shaft and provided with radial arms of different lengths arranged in pairs, rollers mounted in the ends of said arms for engaging 30 said contact devices for opening and closing electric circuits, and means in proximity to stations for effecting the actuation of said rollers and arms.

7. In a car signal device, a pair of channel beams arranged in horizontal alignment on opposite sides of a car top and having their outer ends flaring, contact devices mounted upon the car top intermediately of said channel beams, a shaft above said contact 35 devices, a plurality of hubs rotating on said shaft and provided with radial arms of different lengths arranged in pairs, rollers mounted in the ends of said arms for engaging said contact devices for opening and 40 closing electric circuits, and means in proximity to stations for effecting the actuation of said rollers and arms, in combination with spring-pressed locking devices common to said shaft and hubs.

50 8. In a car signal device, a plurality of operating members each arranged in proximity to a station and comprising a head having at its ends upper and lower and end rollers, a bottom roller located in proximity 55 to said ends, and a movable vehicle having channel beams mounted thereon and provided with flaring ends, the recesses of said channel beams facing each other and adapted to receive said upper and lower and end 60 rollers.

9. In a car signal device, a plurality of contact members carried on the top of a car, a shaft mounted above said members, a plurality of hubs rotating on said shaft and

provided with radial arms thereon, resilient 65 means for locking said hubs in the desired position and rollers mounted on the ends of said arms to actuate said contact member for opening and closing electric circuits.

10. In a car signal device, a plurality of 70 contact members carried on the top of a car, a shaft mounted above said members, a plurality of hubs rotating on said shaft and provided with radial arms arranged in pairs thereon, resilient means for locking said hubs 75 in the desired position and rollers mounted on the ends of said arms to actuate said contact member for opening and closing electric circuits, in combination with a signalling device electrically connected to said hubs and 80 contact members.

11. In a car signal device, a contact member, a shaft mounted above said member, a hub rotatably mounted on said shaft and provided with an arm, a roller mounted on 85 said arm to actuate said contact member, and a signalling device electrically connected to said hub and contact member.

12. In a car signal device, a contact member, a shaft mounted above said member, a hub rotatably mounted on said shaft and provided with an arm, a roller mounted on 90 said arm to actuate said contact member, and a signalling device electrically connected to said hub and contact member in combination with a spring pressed locking device 95 common to said hub and shaft.

13. In a car signal device, a pair of channel beams arranged in horizontal alignment 100 on opposite sides of a car top, a contact device mounted on the car top intermediately of said channel beams, a shaft above said contact device, a hub rotatably mounted on said shaft, and provided with a radial arm, a roller mounted on the end of said arm for 105 engaging said contact device for opening and closing an electric circuit, and means in proximity to a station for actuating said roller and arm.

14. In a car signal device, a pair of channel beams arranged in horizontal alignment on opposite sides of a car top, a contact device mounted on the car top intermediately of said channel beams, a shaft above said contact device, a hub rotatably mounted on 110 said shaft, and provided with a radial arm, a roller mounted on the end of said arm for engaging said contact device for opening and closing an electric circuit, and means in proximity to a station for actuating said 115 roller and arm, in combination with a spring pressed locking device common to said hub and shaft.
